CATTLE FEED TROUGH

Daniel C. Cusenbary, Cunningham, Kans., assignor to
Kingman Manufacturing Co., Incorporated, Cunningham,
Kans.

Filed Apr. 24, 1969, Ser. No. 16,883

Term of patent 14 years

Int. Cl. D30—02
U.S. Cl. D30—13

FIG. 1

FIG. 2

FIG. 3

FIG. 1 is a perspective view of the cattle feed trough with the right end plate removed;

FIG. 2 is a right end elevational view; and

FIG. 3 is a bottom view.

The right end plate, when in place, is identical to the left end plate seen in FIG. 1.

I claim:

The ornamental design for a cattle feed trough, as shown and described.
